UNITED STATES PATENT OFFICE.

FRANKLIN S. SMITH, OF BROOKLYN, NEW YORK, ASSIGNOR TO THE PRODUCTS PROTECTION CORPORATION, OF NEW YORK, N. Y., A CORPORATION OF DELAWARE.

X-RAY-BEAM GENERATOR OF HIGH POWER.

Application filed July 29, 1924, Serial No. 728,986. Renewed January 3, 1927.

My invention relates to that class of X-ray generating apparatus by which very intense X-ray beams are produced. It embodies the hot cathode type of X-ray tube, and has for 5 its principal object the elimination of magnetostriction.

In standard X-ray tubes of the hot cathode type in use at the present time, the effect of the magnetic field of the cathode filament 10 heating current is negligible. For very high powered tubes, however, the magnetic field of the filament heating current is able to inhibit entirely the electron current between cathode and anti-cathode of the X-ray tube. 15 In X-ray tubes embodying cathode filaments of certain configuration, for example a flat spiral as illustrated in the drawing, the electron current may only be inhibited from a part of the cathode filament.

20 It is also an object of my invention to provide means whereby advantage may be taken of the magnetostriction effect referred to for the purpose of controlling the exciting voltage across the X-ray tube.

25 The objects and purposes of my invention will be more fully explained and more readily understood by reference to the drawing accompanying and forming a part of this specification and in which is illustrated schematically an apparatus of simple form embodying the said invention.

30 In the drawing, three circuits, designated 1, 2 and 3 are connected to the electric current supply mains indicated by 4. Each of 35 these circuits will be explained separately, and then an explanation of the system as a whole will be given.

40 Circuit 1 comprises a step down transformer designated as 5. In series with the primary of this transformer is a variable reactance 6. The secondary of the transformer is connected to the cathode filament 7 of the kenotron, designated as a whole by 8. The purpose of this circuit is simply to heat 45 the cathode filament of the said kenotron.

Circuit 2 comprises a step up transformer 9. One end of the secondary is connected to the anode 10 of the kenotron 8. The other end of this winding is connected to one side 50 of a high voltage permittor 11 thru high resistor 12. The other side of the permittor is connected to the center of the secondary of transformer 5, thus completing the charging circuit of the said permittor. In order that 55 the drawing may be as simple as is practical

and consistent with a proper showing of the invention, only half wave rectification of the voltage of transformer 9 has been illustrated. The purpose of this circuit is to unidirectionally charge the permittor 11 which stores 60 the exciting energy for the X-ray tube designated as a whole by 13.

Circuit 3 comprises a one to one ratio transformer 14 the windings of which are insulated from each other for the full voltage of X-ray tube excitation. The secondary of this transformer is connected to the synchronous motor 15 which is direct connected to generator 16. This generator is also direct 65 connected to variable resistor or switch designated as a whole by 17. The purpose of generator 16 is to supply the heating current for the cathode filament 18 of the X-ray tube 13. This filament is illustrated in the drawing 70 as a flat spiral on edge.

The variable resistor 17 functions as a synchronous field resistor of the generator 16. By field control of said generator the heating current thru the cathode filament 18 of the X-ray tube is varied and controlled. The 80 said variable resistor comprises two stationary brushes 19 and 20 which are adapted to contact with the following rotating members:—circular ring sectors 21 and 22, also 85 23 and 24. The two pairs of circular ring sectors are insulated from each other in the same manner in which segments of a commutator are insulated. Circular ring sectors 21 and 22 are connected to each other through 90 high resistor 25; and sectors 23 and 24 are connected to each other through low resistor 26.

When the sectors 23 and 24 are in contact with brushes 19 and 20 the resistor 17 is in 95 position of minimum resistance. In this position the maximum heating current flows through the cathode filament 18 from the generator 16 and magnetostriction is present; that is, the magnetic field of the filament heating current is able to inhibit the electron current between the cathode 18 and the anti-cathode 27 of the X-ray tube.

When, however, only the sectors 21 and 22 are in contact with the brushes 19 and 20, in 100 the relative positions as illustrated in the drawing, then the resistor is in position of maximum resistance. In this position the cathode filament is still incandescent from previous heating, but the filament heating current is at a minimum and magnetostric- 105 110

tion is absent; that is, the magnetic field of the filament heating current is below the critical value and therefore the cathode is in condition for maximum electron emission.

The three circuits which have been described are further interconnected as follows: For the purpose of completing the discharge circuit of permittor 11, connection is made from junction point 28 to the cathode end of the X-ray tube at 29. From the anti-cathode end of the X-ray tube at 30 connection is made to junction point 31. This connection is grounded at 32. This completes the discharge circuit of the permittor 11 through the X-ray tube 13 as will be apparent from the drawing.

In the operation of the system the permittor 11 is charged by rectified current through kenotron 8 by the transformer 9. During this period of charging, the variable resistor 17 is in position of minimum resistance; the X-ray tube then has infinite resistance as magnetostriction is present, that is, the magnetic field of the filament heating current is above the critical value. When the variable resistor 17 is in position of maximum resistance, the position shown in the drawing, magnetostriction is absent and the permittor discharges through the X-ray tube.

This cycle is adaptable to continuous repetition. The periodicity and duration of the X-ray beams may be made as desired, through quite wide limits, by simply synchronizing the variable resistor to the desired periodicity, and by proportioning the peripheral lengths of the circular ring sectors to the desired values. The duration of the X-ray beam is of course influenced by the constants of the permittor discharge circuit.

It will be seen that by my invention I have provided a method and apparatus by the employment of which the lengths of the periods of the production and emission of X-ray beams may be controlled, as well as the lengths of the intervals between such periods.

Having thus described my invention what I claim and desire to secure by Letters Patent is:

1. A high powered X-ray beam generator comprising an X-ray tube embodying a cathode filament, a source of stored X-ray tube exciting energy, a source of cathode exciting energy, and means for varying said filament exciting energy above and below the critical magnetostriction value.

2. A high powered X-ray beam generator comprising an X-ray tube embodying a cathode filament, a high voltage permittor, a filament heating current generator, means for varying the said filament heating current above and below the critical magnetostriction value.

3. A high powered X-ray beam generator comprising an X-ray tube embodying a cathode filament, a high voltage permittor, means

for charging said permittor, a filament heating current generator, and means for increasing the filament heating current to a value greater than the critical magnetostriction value during the period of permittor charging, and means for limiting the filament heating current to a value less than the critical magnetostriction value during the discharge of said permittor.

4. In X-ray apparatus, in combination, an X-ray tube having a cathode filament and a coacting anode, a source of X-ray tube exciting energy connected across said electrodes, and means for controlling the periodicity of the discharge of exciting energy through said X-ray tube and from said source, said means including a source of energy for heating said filament and means for periodically increasing the filament heating current to bring about corresponding periods of inactivity of said source of X-ray tube exciting energy.

5. A high powered X-ray beam generator comprising an X-ray tube embodying a cathode filament, a source of X-ray tube exciting energy, a source of cathode filament heating energy, and means for periodically varying the cathode filament heating energy above and below the critical magnetostriction value.

6. An X-ray beam generator of high power comprising, in combination, an X-ray tube having a cathode filament, a source of high voltage energy which is adapted to be discharged periodically through the said tube, a generator for supplying heating current to said filament and a variable resistor in the field of said generator and adapted for periodically varying the current through said filament whereby magnetostriction caused by the filament heating current within the tube is periodically made ineffective to permit the flow of high voltage energy through said tube.

7. In X-ray apparatus, in combination, an X-ray tube having a cathode filament and a coacting anode; a source of X-ray tube exciting energy connected across said electrodes; and means for controlling the periodicity of the discharge of exciting energy through said X-ray tube and from said source, said means including a source of energy for heating said filament, a resistance for controlling the intensity of heating current flowing to said filament, and means for periodically affecting said resistance to cause periodic energization of said filament cathode at a current value sufficient to effect magnetostriction, thereby to bring about corresponding periods of inactivity of said X-ray tube.

8. In X-ray apparatus, in combination, an X-ray tube having a cathode filament and a coacting anode; means forming a source of relatively high potential for exciting said X-ray tube; and means for controlling the pe-

riodicity of excitation of said X-ray tube by said source, said means including a generator for supplying heating current to said filament, a resistance in the field circuit of said generator, and mechanism for periodically varying the effect of said resistance and adapted to cause said generator to periodically energize said filament cathode at a current value sufficient to effect magnetostriiction, thereby to bring about corresponding periods of inactivity of said X-ray tube.

9. In X-ray apparatus, in combination, an X-ray tube having a cathode filament and a coacting anode, means including a source of alternating current for energizing said X-ray tube, a source of electrical energy capable of energizing said cathode filament at a current value sufficient to effect magnetostriiction and thereby prevent current discharge through said tube, and a synchronous device operated from said source of alternating current for effecting periodic energization of said filament cathode by said second-mentioned source of energy.

10. In X-ray apparatus, in combination, an X-ray tube having a cathode filament and a coacting anode; a source of X-ray tube exciting energy connected across said elec-

trodes; and means for controlling the periodicity of the discharge of exciting energy through said X-ray tube and from said source, including means for periodically energizing said filament cathode at a current value sufficient to effect magnetostriiction, thereby to bring about corresponding periods of inactivity of said source of X-ray tube exciting energy.

11. In X-ray apparatus, in combination, an X-ray tube having a cathode filament and a coacting anode, means including a source of alternating current for energizing said X-ray tube, rotary means for converting alternating current energy from said source to direct current energy and for supplying said filament cathode with the latter, and means operated by said rotary means for periodically causing the latter to energize said filament cathode at a current value sufficient to effect magnetostriiction, thereby to bring about corresponding periods of inactivity of said X-ray tube.

In testimony that I claim the foregoing as my invention, I have hereunto signed my name this twenty-fifth day of July, A. D. 1924.

FRANKLIN S. SMITH.
